by *Robert A. Atty.*

UNITED STATES PATENT OFFICE.

HENRY P. CLAUSEN, OF MOUNT VERNON, AND CHARLES L. GOODRUM, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE SYSTEM.

1,380,357.

Specification of Letters Patent. Patented June 7, 1921.

Application filed December 23, 1918. Serial No. 268,663.

To all whom it may concern:

Be it known that we, HENRY P. CLAUSEN and CHARLES L. GOODRUM, citizens of the United States, residing at Mount Vernon, 5 in the county of Westchester and State of New York, and at New York, in the county of New York and State of New York, respectively, have invented certain new and useful Improvements in Telephone Systems, 10 of which the following is a full, clear, concise, and exact description.

This invention relates to improvements in telephone systems and has particular reference to means for selecting an operator's 15 position.

An object of the invention is to enable an operator to automatically select any one of a number of distant operators' positions over a common wire by means of synchronized 20 distributors.

The inventive idea involved is capable of receiving a variety of expressions one of which, for the purpose of illustrating the invention, is shown in the accompanying 25 drawing; but it is to be expressly understood that said drawing is employed merely for the purpose facilitating the description of the invention as a whole and not to define the limits thereof, reference being had to the 30 appended claims for this purpose.

The drawing illustrates diagrammatically the circuit involving the present invention.

In the drawing 1 and 2 designate the conductors of a telephone line leading to an operator's position A, and 3 and 4 the limbs 35 of a trunk circuit for interconnecting said position with any one of a plurality of operators' positions located at a distant station, two of which are indicated at B and C.

40 The apparatus at the several positions employed for establishing a talking connection may be of any construction well known in the art and a detailed illustration and description thereof is therefore deemed unnecessary. For the purpose of determining the selection of the positions B and C there is provided at position A the keys B' and C', which, when operated, will automatically cause the selection of the positions at the 45 distant station by energizing slow-to-release relays 5 and 6. Energization of these relays is controlled by distributors 7 and 8, one of 50 which is located at each station, and which are of any well known construction and op-

erated in synchronism by any means common in the art. Joining these distributors is a common conductor 9 over which the connection for energizing either of the relays 5 or 6 is established.

It is believed that the invention will now 55 be fully understood from a description of the operation. Should the operator at position A desire connection to the operator at position B, the key B' is operated and as soon as the wipers of the distributors 7 and 8 engage the contacts to which conductors 60 10 and 11 are connected, a circuit will be closed for relay 5 extending from grounded battery, winding of relay 5, conductor 11, wiper of distributor 8, conductor 9, wiper of 65 distributor 7, conductor 10, contact 12 and spring 13 of key B' to ground. Relay 5 is energized and closes a circuit including the telephone line leading to the operator's apparatus at position B. Relay 5 is made 70 slow-to-release so that the same will not become deenergized during a complete revolution of the wipers of distributors 7 and 8 and the circuit to station B will therefore be maintained closed as long as key B' remains 75 operated. A talking connection will now be established between the operators at positions A and B extending from the apparatus of position A, conductor 1, contact 14 and its associated spring, limb 3, inner armature 80 and front contact of relay 5, apparatus at 85 position B, front contact and outer armature of relay 5, limb 4, spring 15 and its associated contact and conductor 2 to the apparatus at position A. At the termination of 90 a conversation, release of key B' will remove ground from the conductor 10 and thus cause the deenergization of relay 5, which, in retracting its armatures, breaks the talking 95 circuit between positions A and B.

In the same manner as above set forth, the operator at position A may connect her apparatus to that at position C by operating key C' to energize slow-to-release relay 6, which maintains the talking connection until 100 key C' is released.

What is claimed is:

1. In a telephone system, a plurality of operators' positions, means at one of said positions for determining the selection of 105 any one of the other positions, means operated to select the position determined by the first named means, synchronized means

connecting the first and second named means for controlling the operation of the latter, and a common talking circuit completed by the operation of the second named means for 5 interconnecting the first named position with said other position.

2. In a telephone system, a plurality of operators' positions, means at one of said positions for determining the selection of any 10 one of the other positions, a relay operated to select the position determined by the first named means, synchronized distributor connecting the first named means and said relay for controlling the operation of the latter, 15 and a common talking circuit completed through the contacts of said relay for interconnecting the first named position with said other position.

3. In a telephone system, a plurality of operators' positions, a common talking circuit for interconnecting said positions, means at one of said positions for determining the selection of any one of the other positions, a relay operated independently of said talking circuit to select the position determined by the first named means and to complete through its contacts the talking circuit between the first named and selected positions, and synchronized means connecting the first named means and said relay for 30 controlling the operation of the latter.

In witness whereof we hereunto subscribe our names this 12th day of December, A. D. 1918.

HENRY P. CLAUSEN.
CHARLES L. GOODRUM.
